FIG. 8

By John W. Otto
Attorney.

UNITED STATES PATENT OFFICE

GEORGE W. OTTO, OF COLLINGSWOOD, NEW JERSEY

BOTTLE-SUSPENSION DEVICE

REISSUED

Application filed March 3, 1927. Serial No. 172,223.

The object of my invention is to provide a simple, inexpensive and efficient suspension device for milk bottles and the like to enable them to be suspended out of reach of cats and dogs, and further, off the ground or steps where they have heretofore been subjected to the accumulations of dust and dirt put in motion by the wind and otherwise, thereby increasing the sanitary conditions under 10 which milk may reach the consumer.

My improvement consists of a bracket structure adapted to be attached to a window sill, door frame, porch post or other suitable place above the ground, floor or steps, and 15 provided with a yoke within which the neck of a bottle may be received and upon which the beaded upper part or mouth of the bottle may be suspended, said yoke provided with means to retain the bottle against accidental 20 displacement.

My invention further consists in a lid or cover element carried by the yoke and arranged above the same whereby it may rest over the mouth of the bottle when in position 25 upon the yoke, and said cover provided, if desired, with means to retain the bottle neck within the yoke.

My invention also comprehends details of construction which, together with the features above enumerated, are fully described hereinafter and more particularly pointed out in the claim.

Referring to the drawing: Fig. 1 is a side elevation of a suspension device embodying 35 my improvements, with a bottle in place; Fig. 2 is a plain view of the same; Fig. 3 is a perspective view illustrating the suspension device with the bottle removed; Fig. 4 is a side view of a modified construction of my improvements; Fig. 5 is a plan view of the same; Fig. 6 is a plan view illustrating a plurality of the suspension devices formed on the same bracket or bar; Fig. 7 is a side elevation and 40 Fig. 8 a sectional plan view of the same, on line 8—8 of a modified form of the device; and Fig. 9 is a perspective view of the lid structure thereof.

2 is a bracket adapted to project forward from a flanged or bar-shaped portion 3 which 50 may be attached to a window sill, porch post,

door frame or other suitable place, by one or more screws 15, the said bracket terminating at its forward part in a U-shaped yoke 4 having a throat opening 5 between the arms thereof sufficient to receive the neck 6 of an ordinary milk or other bottle. The upper surface 9 of the yoke provides a semi-circular wall upon which the bead or lip portion 7 of the bottle may rest, thereby holding the bottle in a suspended condition while being 60 positioned by the throat 5 of the yoke 4.

In the particular construction shown in Figs. 1, 2 and 3, the forward ends of the arms of the yoke 4 are provided with upwardly projecting portions 8 which act as locking obstructions against the outward shift of the body portion 7 of the bottle neck, and in this way insures the bottle being retained by the suspension means without danger of its slipping out of the yoke. As the bottle is suspended in this manner when fully loaded with milk, its weight operates to hold it definitely in position in the yoke back of the locking obstructions 8, and yet permits it to be freely raised so that the body portion 7 70 may clear the said obstructions when it is desired to disengage the bottle.

Hinged to the bracket 2 on the pin 12 at the rear of the yoke portion is a cover plate 10 which is provided with lugs 11 hinged upon the said pin 12. Preferably, there is sufficient looseness by the clearance 14 in connection with the hinged joint which will permit the cover plate 10 to fit horizontally upon and over the mouth of the bottle while allowing for slight variations in the height of the bottle mouth above the yoke surface 9. As shown, the cover plate 10 may be provided at its front portion with a downwardly extending tooth 13 which will project downward in front of the bottle neck, as shown, and act as a further means for retaining the bottle against accidental displacement from the yoke. It will be manifest that either or both of the retaining means 8 and 13 may be employed to prevent disengagement of the bottle, as preferred.

In using my improvement when there is no bottle in position, the cover plate 10 will rest upon the outer ends of the yoke arms 3, and 100

when the bottle is to be positioned, the upper edge of the neck is pressed upward under the projecting tooth 13 and lifts the cover plate sufficiently high to enable the bead portion 7 of the bottle neck to pass over and back of the obstructing portions 8 to the position shown in Fig. 1. When this position is reached, the cover plate 10 will be resting flat over the mouth of the bottle and the tooth 13 will be in front of the bead portion 7 of the bottle neck to temporarily lock the same in position.

To disengage the bottle, it is only necessary to lift the same and thereby cause the cover plate to be tilted upward sufficiently for the tooth 13 to clear the bottle, and thereupon move the bottle forward out of the yoke. Of course, it will be understood that the cover plate 10 may be manipulated by hand, if so desired.

In Figs. 4 and 5, I have shown a modification of my improvement, wherein the obstructing portions 8 are omitted from the yoke 4 and a spring clamping means is provided to grip the neck 6 of the bottle when the same is pushed back into the yoke. As shown, the spring portions constitute two spring arms 8^a formed as an integral U-shaped structure which is riveted at its rear end to the yoke 4 by the rivet 16. By this means, the bottle neck need only be pushed backward into the throat 5 of the yoke wherein it will be retained by the spring action of the said arms 8^a. These spring arms may be arranged in any other suitable manner, if so desired. A hinged cover plate 10 may be arranged on the bracket 2 in substantially the same manner as in the case of Fig. 1.

While I have shown definite means for retaining the bottles against accidental displacement from the yokes, I do not confine myself to the particular means shown, as it will be evident that other forms of retaining means may be adapted to the yoke structure, if so desired.

While my suspension devices may be made as independent structures separately attached to the window sill or other place of convenience, where a number of them are to be employed for the same residence, they may be connected by a backing plate 3 of a length sufficient to permit properly spacing the suspension devices and be attached as a whole to the window frame or other place of support, as shown in Fig. 6.

While the broader features of my invention are disclosed in Figs. 1 to 5, inclusive, the same may be modified to still further improve the commercial article by increasing its sanitary qualities by wholly enclosing the neck and mouth portion of the bottle, and these improvements are fully illustrated in Figs. 7, 8 and 9, having the following features. The bracket 2 with its supporting flanged portion 3 may correspond to the

structures already described, and similarly, the throat portion 5 for receiving the bottle neck may be formed with a yoke portion 4 and 9 corresponding in general to that already described, but in this case, the outer portions of the curved yoke are extended upwardly as at 4^a to a level slightly above the top of the bottle rim 7, thereby providing a housing to the yoke to shield the mouth of the bottle. The lid or cover plate 10 is hinged to the bracket by the parts 11, 12 and 14, as before described in connection with Fig. 1, and will need no further description in this respect. This lid, however, is arranged to rest upon the upwardly projecting housing portion 4^a of the yoke 4, so that it forms a seal connection. The forward part of the lid has the downwardly extending apron part 13^a which, preferably, extends down to the bottom of the yoke 4, and with lateral edges brought into substantial abutting relation with the forward edges of the said yoke. In this manner, the apron portion 13^a constitutes a retaining means to prevent the bottle neck from disengagement from the yoke, and, in effect, performs the retaining results of the downwardly projecting tooth portion 13 of Fig. 1 before described, but in this case, the apron is extended laterally to cooperate with the portions 4^a of the yoke for more fully shielding the bottle neck and mouth of the bottle from exposure. The top of the plate or lid may be slightly crowned or inclined to more readily shed the rain water. The lid portions cover the bottle mouth, keeping rain and dirt out of contact therewith, and the shielding features keep insects from finding access to the bottle mouth and also protects the same from accumulations of dirt which may be carried through the air on windy days as well as adding further security against cats who might succeed in reaching the suspension device, notwithstanding its elevation from the ground.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim and desire to secure by Letters Patent is:

A suspension device for supporting milk bottles, consisting of a bracket having means for attachment to a window sill or other suitable place and provided with a forwardly directed U shaped throat portion having a

width of opening to receive the head of a
bottle neck to be suspended, the forward ends
of said throat portion having an upward ex-
tension to retain the bottle neck within the
throat portion and said extensions continued
5 rearwardly as shielding portions to the out-
side of the bottle neck, combined with a cover
plate or lid adapted to extend over the for-
ward extensions of the throat and having
10 downwardly extending portions at the front
acting both as a shield to the bottle neck, and
said lid or cover having a loose connection
with the bracket at the rear of the throat the
same constituting a hinge and at the same
15 time to permit bodily movement of the entire
lid or cover relatively to the bracket and its
throat portions, whereby said lid or cover
may at all times operate as a sealing means to
the throat or to the bottle neck according to
20 which may be the higher.

In testimony of which invention, I here-
unto set my hand.

GEORGE WM. OTTO.
